HEAD BOARD FOR A BED

Jerome S. Tomaszkiewicz, 315 Hackberry St.,
Millard, Nebr.

Filed Sept. 21, 1964, Ser. No. 81,808

Term of patent 14 years

(Cl. D5—4)

FIGURE 1 is a perspective view of the head board showing my new design.

FIGURE 2 is a rear elevation of the head board of FIGURE 1.

FIGURE 3 is a side elevation of FIGURE 1.

I claim:

The ornamental design for a head board for a bed, as shown.
